ATTORNEY

UNITED STATES PATENT OFFICE.

SAMUEL E. MAXWELL, OF AVALON, PENNSYLVANIA.

HEATER.

1,147,878.

Specification of Letters Patent. Patented July 27, 1915.

Application filed October 30, 1914. Serial No. 869,368.

To all whom it may concern:

Be it known that I, SAMUEL E. MAXWELL, a citizen of the United States, residing at Avalon, in the county of Allegheny and State of Pennsylvania, have invented a certain new and useful Improvement in Heaters, of which the following is a specification.

My invention relates to heating appliances of the radiating type, designed principally for utilizing natural gas or other similar fuel, whereby a maximum heat efficiency will prevail with a minimum consumption of gas. In addition I provide means for insuring perfect mixing and combustion of the air and gas thereby eliminating odors or noxious fumes.

I am aware that heating devices of a somewhat similar nature and intention have been patented, but my invention resides primarily in providing an upper disposed compartment for collecting the products of combustion before they are allowed to enter the room in which compartment all carbon or other foreign matter given off by the ignited air and gas, or drawn into the heater by the natural draft, will be deposited, which feature is of practical advantage and will be appreciated by those skilled in the art.

The comparatively few parts entering into the construction of my heater insures cheapness of manufacture, both as to material and labor for assembling, at the same time providing the maximum of radiating area.

In the accompanying drawing is shown one embodiment of my invention, which I desire it understood is merely illustrative, the same being subject to such alteration and amendment as future practice and experimenting may dictate.

Constructively my device, as disclosed in the accompanying drawing, involves a suitable base portion 1, which I intend constructing out of some bright reflecting material, such as copper, brass, or nickel, said base being of suitable configuration, and supported on legs 2. Passing up through the said base, and extending to a predetermined height thereabove, is a hollow column or riser 3 which acts as a conducting means for the fuel gas supplied by a pipe 4 and in addition supports a suitable burner 5 adjacent to its upper extremity. Adequately supported by the said column above the burner is an outwardly flared hollow cone-shaped member 6, which performs the func-

tion of a deflecting means, while above this latter described portion, and suitably spaced-apart therefrom, is a second hollow cone-shaped member 7 of somewhat less diameter than the said member 6, also supported by the column 3. The walls of this said element 7 are provided with a plurality of suitable sized apertures 8, and the outer rim is provided with a flange 9 in order to insure an engaging or fastening means in conjunction with the surrounding dome 10, to which said member 7 is secured by clips 11 or any other adequate means. The apex of said dome is here shown as being slightly raised above the main body portion thereby forming a hollow cap or recess of predetermined diameter, which said recess, taken in conjunction with the space formed by the inner walls of the member 7, forms an upper central compartment 12. Said cap or apex of the dome is provided with a plurality of apertures 13 to insure a natural draft and egress of the heated air from the said compartment. The vertically disposed side walls of said dome which may be of solid formation or grilles as shown, preferably extend to a point below the horizontal line of the burner in order to encompass and partially conceal said burner coupled with their function as radiating portions of the heater, said walls being subjected to the heat from the burner. It will be observed that the under side of said dome is open on all sides to the atmosphere in order that the ignited gas is assured a sufficiency of air for proper combustion and in addition that the heater will be supplied with a proper amount of fresh air to be heated and expelled into the room.

The flame will be deflected outward toward the side walls of the dome by the member 6 the heat or products of combustion passing upward through the space 14, thence into the communicating space 15 between the two members 6 and 7, then into the compartment 12 through the apertures 8, in which compartment the carbon or other foreign matter carried thereto by the ignited gas and air will be deposited, the clean heated air finally passing out of the heater by way of the apertures 13.

In order to prevent a too ready escape of the heated air from the central chamber 12 I have provided a perforated baffle or screen 16, which can be positioned horizontally of the said chamber as shown, preferably ad-

5 jacent to the upper section or apex of the dome between the entrance and exit apertures, which baffle tends to aid in the deposit of carbon or other elements held in suspen-

10 sion in the fuel gas and air. It will be apparent that my form of heater affords the maximum of radiating area in that the dome and deflecting member will give off heat in all directions, due to the open formation of the device, and in addition the base portion 1 will likewise become heated and give off its proportion of radiation.

15 The clip members 11 carried by the dome, coöoperating with the roof of said dome and flanged upper portion of the inner cone, affords a ready means for removably locking said dome in position, from whence it can be quickly disengaged should it be necessary to uncover the inner compartment for cleaning purposes.

20 What I claim as my invention is:—

25 1. A heating appliance having a suitable base; a hollow column rising above the base, said column acting as a conducting means for the fuel supply; a burner carried by the column in communication with the fuel supply means; a hollow inverted cone-shaped deflecting member above the burner; a sec-
30 ond hollow inverted cone-shaped member interior of and spaced-apart from the said deflecting member, the walls of which are perforated; a dome supported by the inner disposed cone, the apex of said dome being per-
35 forated and forming a hollow cap portion which, taken in conjunction with the said inner cone, forms an inner compartment; and means carried by the dome for remov-
40 ably securing said dome in position.

45 2. A heating appliance having a suitable base; a hollow column rising above the base, said column acting as a conducting means

for the fuel supply; a burner carried by the column in communication with the fuel supply means; a hollow inverted cone-shaped deflecting member above the burner; a sec-
50 ond hollow inverted cone-shaped member interior of and spaced-apart from the said deflecting member, the walls of which are perforated; an inclosing dome supported by the inner disposed cone, the apex of said dome being perforated and forming a hollow cap portion, which, taken in conjunction with the said inner cone, forms an inner compartment; and clip members carried by the dome for removably locking said dome to the said inner cone.

55 3. A heating appliance having a suitable base; a hollow column rising above the base, said column acting as a conducting means for the fuel supply; a burner carried by the column in communication with the fuel supply means; a hollow inverted cone-shaped deflecting member above the burner; a sec-
60 ond hollow inverted cone-shaped member interior of and spaced-apart from the said deflecting member, having perforated walls column in communication with the fuel sup-
65 ported by the inner disposed cone, the apex of said dome being perforated and forming a hollow cap portion, which, taken in con-
70 junction with the said inner cone, forms an inner compartment; clip members carried by the dome for engagement with the flanged portion of the inner cone for removably locking said dome in position; and a screen interior of the said inner compartment removably held in position by the said clips.

75 In testimony whereof I affix my signature in the presence of two witnesses.

SAMUEL E. MAXWELL.
